UNITED STATES PATENT OFFICE.

JOHN A. PERKINS, OF MINNEAPOLIS, MINNESOTA.

GRAIN SEPARATOR.

Application filed October 5, 1925. Serial No. 60,482.

This invention relates to new and useful improvements in grain separators; generally, and more particularly relates to such separators of the type employing an inclined belt 5 having an indented or pocketed surface onto which the material to be separated is delivered.

An object of the invention is to provide a flexible separating belt for a grain separator having its outer surface covered with a plurality of suitable pockets adapted to receive material, and the walls between said pockets being flexible so as to permit the pockets to elongate or enlarge as the belt 10 passes over a supporting roll, thereby causing the pockets to more readily discharge the material being conveyed, and increasing the speed and capacity of the separator.

A further object of the invention is to provide a grain separator having an inclined indented separating belt mounted therein and said belt having means cooperating therewith to prevent leakage of the material from the belt's surface when in 25 operation.

A further and more specific object is to provide such a separator having inclined guards or guides arranged on each side of the separating belt adjacent the upper surface thereof, thereby causing the material to be continually traveling into a wider area with the result that it cannot possibly escape over the sides thereof.

The particular object of the invention, therefore, is to provide an improved separating belt for grain separators which is an improvement over the form shown in my U. S. application, Serial No. 678,312, filed December 3, 1923.

40 Other objects of the invention will appear from the following description and the accompanying drawings and will be pointed out in the annexed claims.

In the drawings, there has been disclosed a structure designed to carry out the various objects of the invention, but it is to be understood that the invention is not confined to the exact features shown as various changes may be made within the scope of the claims 50 which follow.

In the accompanying drawings forming part of this specification,

Figure 1 is a vertical sectional view through a separator showing my improved 55 separating belt mounted therein;

Figure 2 is a sectional plan view on the

line 2-2 of Figure 1 showing the inclined guards or seals provided on each side of the belt to prevent leakage therefrom;

Figure 3 is an enlarged detail sectional view on the line 3-3 of Figure 2;

Figure 4 is an enlarged detail plan view of a portion of the belt's surface showing how the flexible walls between the pockets will yield to permit the pockets to enlarge 65 and assume a different shape as they pass over the supporting roll at the discharge end of the machine;

Figure 5 is a detail sectional view showing a portion of the belt positioned upon 70 its supporting roll; and

Figures 6 and 7 are detail views showing guards of modified constructions.

In the selected embodiment of the invention here shown, for purposes of disclosure, 75 there is illustrated a grain separator comprising a casing 11 mounted upon suitable blocks 12, as shown in Figure 1. A receiving opening 13 is provided in the upper wall of the casing into which the material to be separated may be delivered onto the inclined surface of the separating belt 14 mounted upon suitable rollers 15 within the casing 11.

An inclined plate 16 is secured to the 85 right-hand wall of the casing 11 and cooperates with the inclined surface of the belt 11 to provide a trough-like receiving means for the material delivered through the opening 13. This wall or plate 16 is 90 preferably arranged at an incline with relation to the axis of the shaft 17 of the lower roll 15, as clearly shown in Figure 2. The purpose of thus arranging the plate 16 on an incline with relation to the shaft 17 is 95 to cause the relatively coarser material, which is too large to be conveyed by the indented or pocketed surface of the belt, to travel towards one side of the machine and be discharged through a spout 18 into a 100 suitable receiving means, not shown. A hopper 19 having a spout 21 leading therefrom, is preferably arranged at the rear of the machine to receive the separated material which is conveyed to the rear of the 105 machine by the belt, as shown in Figure 1.

A feature of this invention resides in the novel construction of the separating belt mounted upon the supporting rollers 15. The surface of this belt, as shown in the 110 drawings, is substantially covered with a plurality of indentations or pockets 22

which are formed by the transverse walls 23 and the relatively short walls 24, preferably arranged in staggered relation as clearly shown in Figure 4. The transverse walls 23 are preferably undercut or arranged at an incline as shown in Figure 5 so as to receive and convey the material to the rear of the machine. The relatively shorter walls 24 are preferably vertical and are arranged in staggered relation as shown to cause the transverse walls 23 to be pulled or stretched into the shape or form shown on the left hand side of Figure 4, as the belt passes over the upper supporting roll 15. The separating belt 14 is constructed of a suitable flexible material such, for instance, as rubber which is suitably reinforced by canvas or fabric, such as is customary in structures of this character.

By thus constructing the upper indented surface of the belt of a flexible and elastic material as above described, the pockets 22, in passing over the rolls 15, will be elongated or enlarged to readily discharge the material therefrom into the receiving hopper 19. By thus enlarging the pockets to discharge the material, the relative speed of the separating belt may be considerably increased, thereby increasing the capacity of the separator.

Another feature of this invention resides in the novel means provided for preventing leakage of the material from the belt while the separator is in operation. Such means preferably consists of a pair of inclined guards or guides 25 suitably secured to the end walls 26 of the casing 11 with their lower faces 27 arranged over the surface of the belt in close proximity thereto but, as shown in Figures 3, 6 and 7 out of contact therewith. The relatively larger and wider ends of the guards 25 preferably abut against the inclined cross wall 16 as shown in Figure 2. By thus arranging the guards 25 over the separating belt 14, the portion of the belt's surface onto which the material to be separated is delivered for separation, will be relatively smaller in area so that as the material is conveyed upwardly by the pockets 22 in the belt's surface, it will constantly be traveling into a relatively wider area, thereby positively preventing any of the material from wedging under the guards 25 and dropping off the edges of the belt. The inner walls 28 of the guards 25 are preferably inclined as shown in Figure 3, so as to direct the material inwardly away from the edges of the belt. The guards 25 are also preferably formed and constructed as shown in Figures 2 and 3, but, if desired, they may be shaped as shown in Figures 6 and 7, it being understood that the primary purpose of the guards is to prevent leakage of the material at the sides of the belt by decreasing in area the effective receiving portion of the belt's surface and causing the

material being conveyed to travel into a relatively wider area and away from the guards as indicated in Figure 2, thereby positively preventing the material from becoming wedged between the guards and the belt's surface, or working out over the edges of the belt.

In the operation of this novel grain separator the material to be separated is delivered through the opening 13 into the trough-like receiving means formed by the upper inclined surface of the belt and the inclined wall 16, shown in Figure 1. The pockets 22 in the belt's surface are of such size to receive material of a given size such, for instance, as when separating wheat from oats or coarser material. As the material is delivered onto the belt's surface, which is constantly traveling in the direction indicated by the arrows in Figure 1, the material will be constantly agitated so that all of the material of the mass will come in contact with the indented surface of the belt and the material to be separated will drop into the pockets and will be conveyed upwardly to the rear of the machine and be discharged into the hopper 19, as clearly shown in Figure 1. As a result of the pocket walls being constructed of a flexible material, they will, in passing over the periphery of the upper roll 15, be pulled or stretched substantially to the form shown on the left hand side of Figure 4, thereby causing the material being conveyed thereby to be discharged into the hopper 19 without any danger of it being carried to the lower portion of the casing 11.

The lighter and coarser material will gradually work to the top of the mass of grain deposited upon the lower inclined surface of the belt, and as a result of the plate 16 being arranged on an incline, as shown in Figure 2, the coarser and lighter material will gradually travel across the machine to the discharge spout 18 from which it may be discharged to a suitable receiving means, not shown.

The inclined guards or guides 25 will cause the material to be continually traveling into a wider area as a result of the belt traveling from beneath the guards as indicated by the arrows in Figure 2. By the employment of these guards, therefore, the material will appear as if constantly traveling away from the sides of the belt, thereby positively preventing any of the material from working or wedging between the upper surface of the belt and the lower faces 27 of the inclined guards or seals 25.

In the drawings, I have shown the belt's surface as being covered with pockets of uniform size, but it is to be understood that, if desired, pockets of various sizes may be employed for the purpose of adapting the machine for separating different materials

from one another. The particular shape and form of the guards or guides 25 may also be varied in many ways without departing from the invention, it being understood that the primary purpose of the guards is to provide means for partially covering the receiving portion of the belt surface so as to cause the material being separated to be continually traveling away from the guards 10 25 and the edges of the belt.

I have shown and described these guards or guides used with an endless belt to prevent the material from working laterally over the edges thereof and to guide such 15 material forwardly away from such edges. I do not wish, however, to confine myself to the application or use of these guides with a belt as this feature of the invention may be used with other forms of separators or 20 with revolving drums such as are used in scalpers and revolving screens where difficulty is experienced in keeping the material from working off the edges. The principle involved and the method of operation would 25 be substantially the same as shown herein and detailed illustration and description is, therefore, considered unnecessary.

I have disclosed in the foregoing specification and the drawings the preferred form 30 of my invention but I do not limit myself to the details of construction shown and described except as the same come within the scope of the following claims.

I claim as my invention:

35 1. A machine of the class described comprising a retaining means for the material to be separated, an endless belt having flexible pockets in its outer surface the walls of which are thin and substantially of uniform thickness throughout and always 40 closed at the inner side of said belt and open at the outer side thereof and adapted to receive certain kinds of material from the co-mingled body in said retaining means and 45 adapted to be distended and assume another shape to discharge the material at a point higher up than the point where it is received, but on the same side of the belt as the point of reception of the material.

50 2. In a machine of the class described, a separator having a series of pockets in its surface, said pockets being closed at the bottom normally of a shape to receive the material and adapted to change their shape 55 and become elongated or enlarged across the full width of the working surface of the separator at a predetermined point in the movement of the separator for the rapid discharge of the material collected therein.

60 3. In a machine of the class described, an endless belt having a series of pockets in its surface adapted to collect and separate fine from coarser material, said pockets being closed at the bottom and normally having a certain shape to receive the material

and provided with flexible walls adapted for elongation the entire width of the working surface to assume another shape at a predetermined point in the movement of the belt for the rapid discharge of the material 70 in the pockets.

4. In a machine of the class described, a traveling separator having a surface composed of flexible resilient material and provided with a series of pockets adapted to collect and separate fine from coarser material, the walls of said pockets being capable of expansion or separation at a predetermined point in the movement of the separator for the convenient discharge of 80 the material collected in the pockets and guards overhanging the edges of the separator and formed so that the separator edges moving forwardly from under said guards will tend to carry the material away from 85 said guards.

5. In a machine of the class described, a separator adapted to receive and separate fine from coarse material and means for delivering the material upon the surface 90 of said separator, guards substantially out of contact with but overhanging the edges of the separator and having their under surfaces parallel with and adjacent the surface of said separator and preventing the material from working off the edges thereof, and decreasing in width from the point of delivery of the material to said separator toward the point of discharge therefrom 95 whereby the motion of the separator will 100 direct the material away from the gap between the guards and separator.

6. A separator comprising a container for material to be separated, an endless pocketed belt and tapered guards with their small 105 ends extending in the direction of the belt's travel and one side or edge in close proximity to the belt's surface but out of contact therewith so that the pocketed surface of the belt is continually traveling into a wider area from under said guard, thus preventing the material from falling off the sides or edges of said belt.

7. A separator comprising a container for material to be separated, an endless pocketed belt and angular guards overhanging the side margins of said belt and out of contact with the belt, the lower portions of said guards being wider thus extending farther in from the belt's margin and the smaller ends pointing in the direction of the belt's travel and closer to the margins of said belt so that the pocketed surface of the belt is continually traveling into a wider area from under said guards.

8. A machine of the class described, upper and lower rolls and an endless belt arranged at an incline on said rolls, means for holding the material to be separated upon the lower portion of the upper run or stretch of said 120 125 130

- 5 belt, said belt having a plurality of pockets normally substantially rectangular in form in its surface, the bottoms of said pockets being closed and adapted to receive the finer material and the adjacent pockets having comparatively thin flexible walls separating them one from the other, said walls being capable of distension to enlarge and change the shape of said pockets as they pass over 10 the rolls whereby said pockets will assume an elongated form and the finer material collected in said pockets will be completely and rapidly discharged at a predetermined point in the movement of the belt.
- 15 9. In a machine of the class described, a separator having a series of pockets in its surface adapted to collect fine material to separate it from coarser material and guard members overhanging the edges of said separator and having their under surfaces normally out of contact with the surface of said separator, said guard members also having under surfaces decreasing in width from the receiving point of the material on said 20 separator toward the discharge point thereof, so that the outer pockets of said separator are traveling continuously into a wider area from under said guards.
- 25 10. A machine of the class described, comprising a traveling separator having indentations or pockets to receive relatively fine material and separate it from coarser material, and guard members overhanging the edges of said separator adjacent its separating surface but normally out of contact therewith and having diverging, inner faces, the outer indentations being adapted to travel from under said guards and receive the fine material and cooperate with the adjacent diverging surfaces of said guards to deflect such material inwardly from said guards and close or seal the entrance to the gap between said separator and guards.
- 30 11. A machine of the class described comprising a traveling separator having pockets in its surface for the separation of fine from coarse material, and guard members overhanging the edges of said separator in close proximity thereto but normally out of contact therewith, said members having non-yielding faces so formed that the outer pockets of said separator travel from under said members into a space between them that increases in width toward the discharging 35 point of said separator.
- 40 12. A machine of the class described, comprising a traveling separator adapted to separate fine from coarse material, and guard members arranged to overhang the edges of said separator on each side thereof, said members being composed of tapered blocks having under surfaces parallel substantially

with the upper surface of said separator and adjacent thereto, but substantially out of contact therewith, said guard members decreasing in cross-sectional area from the point of reception of the material on said belt, toward the discharge point thereof, so that said separator is traveling continuously into a wider area from under said guard members.

13. The combination with a casing, of a traveling conveyer mounted to operate at an incline therein and having a surface for separating fine from coarse material, and guards mounted upon each side of said conveyer and overhanging the edges thereof but separated therefrom and extending lengthwise of the conveyer, said guards having surfaces in close proximity to the surfaces of the conveyor, the opposing faces of said guards being formed to cooperate with said conveyor moving thereunder to direct the body of material on the conveyer away from the guards.

14. A traveling conveyor, a substantially rigid guard member overhanging and closely adjacent an edge of said conveyor, the overhanging edge of the guard member extending diagonally to the direction of motion of the conveyor and the guard member being continuously out of contact with the conveyor.

15. A traveling separator having indentations to receive relatively fine material and separate it from coarser material, and guard members overhanging the edges of said separator, but substantially out of contact therewith, the indentations receiving the fine material, and said guards being so formed and positioned with respect to said separator that the material will be directed forwardly away from the guards into a wider exposed area on said separator.

16. In a machine of the class described an endless separator belt having a series of pockets formed in its upper surface said pockets being closed at the bottom and extending transversely of the belt, and having comparatively thin walls of substantially the same thickness throughout for separating the adjacent transverse pockets, the pockets normally being adapted to receive the material to be separated, the finer material falling into the pockets, the narrow walls between the pockets becoming distended at a predetermined point in the movement of the belt and separating the opposite end walls of the pockets whereby the finer material collected in the pockets will be rapidly discharged.

In witness whereof, I have hereunto set my hand this 14th day of September 1925.

JOHN A. PERKINS.
